INVENTOR
P. Mark Weddell

BY John A. Bainbridge
HIS ATTORNEY

UNITED STATES PATENT OFFICE.

P MARK WEDDELL, OF SAN JOSE, CALIFORNIA.

PROPELLER.

1,326,701.

Specification of Letters Patent. Patented Dec. 30, 1919.

Application filed August 26, 1919. Serial No. 320,055.

To all whom it may concern:

Be it known that I, P MARK WEDDELL, a citizen of the United States, and a resident of San Jose, in the county of Santa Clara and State of California, have invented certain new and useful Improvements in Propellers, of which the following is a specification.

My invention relates to adjustable propeller blades, and the object of my invention is to provide a mounting for propeller blades whereby they may be axially rotated at the will of the operator. Further objects are, to provide a mounting of the character indicated that provides gear connections between the blades at their inner ends so that an adjustment of one blade will effect a corresponding adjustment of the other blade in the opposite direction, and in which all of the parts are so positioned with relation to each other that a strong, durable, easily operated propeller is secured, and one in which all parts thereof may be perfectly balanced in any and all positions of the blades.

In the drawing:

Figure 1 is a vertical, longitudinal, sectional view through the propeller mounting forming the basis of this invention, with the blades extended horizontally.

Fig. 2 is a horizontal sectional view through the propeller mounting shown in Fig. 1 with blades extended vertically, with operating means attached thereto, and with parts broken away.

Fig. 3 is a sectional view on 3—3 of Fig. 1.

Referring more particularly to the drawing, at 1 I show a housing of suitable size and form, in which are formed bearings 2 and 3 for shafts 4 and 5 respectively. Shafts 4 and 5 carry sockets 6 and 7 respectively in which are securely bolted propeller blades 8 and 9. On the inner squared ends 45 of shafts 4 and 5 are secured opposing bevel gears 10 and 11. Shafts 4 and 5 are provided with threaded portions as 12 and 13 with intermediate smooth portions as 14 and 15, and locking blocks 16 and 17 are also 50 provided with threaded portions as 18 and 19 and intermediate smooth portions 20 and 21, so that the said blocks 16 and 17 may be slipped into position on their respective shafts, turned a distance thereon to engage 55 the corresponding threaded portions of said shafts and fastened against further rotation

thereon by any suitable means as pins 22 and 23 locked to gears 10 and 11 against accidental displacement.

In the present case I have shown propeller shaft 24 passing through housing 1 and keyed thereto and secured against accidental displacement therefrom. Rotatably mounted on shaft 24 and on pins 25 and 26 set in housing 1, are pinions 27—28—29 and 30 in permanent engagement with bevel gears 10 and 11.

Any suitable means may be provided for adjusting blades 8 and 9 such as collar 31 slidably mounted on shaft 24 and prevented from turning thereon by key 32, and carrying arms 33 and 34 attached to opposite sides of sockets 6 and 7 as at 35 and 36. This collar is shifted by means of yoke 37 engaging collar 31 and rod 38 connected to lever 39, the latter being mounted on a suitable quadrant 40 where it may be locked in any desired position by means of catch 41.

In assembling the device the propeller blades are placed in position with shafts 4 and 5 extending into housing 1, blocks 16 and 17 are then slipped into position thereon and turned to engage the threaded portions of said shafts. The gears 10 and 11 are now secured on their respective shafts and keyed to blocks 16 and 17. The shaft 24 and pinions 27—28—29 and 30 having been placed in position the housing is bolted together and the operating mechanism assembled and connected to the sockets as shown.

It is now clear that the propeller may now be driven at any desired speed and the blades will be fixed against displacement from the shaft 24. By means of the adjusting mechanism the blades may be rotated to any desired degree in either direction thereby enabling the operator to meet a wide variation of air conditions (when used on an air craft) without altering the speed of the engine. This feature is especially advantageous when the device is mounted upon a dirigible balloon as it enables the operator to quickly shift the blades to a reverse position thereby utilizing them as a brake, and at all times giving the operator a more perfect control over the dirigible than is possible with the present equipment, and this without necessarily altering the speed of the engines of the aircraft.

Another feature of special advantage in

this form of construction is that the gear mechanism being always in mesh it acts as a lock against automatic adjustment of the blades as they may be constructed to balance 5 perfectly so that the tendency of one blade to revolve on its axis in one direction is offset by the equal tendency of the other blade to revolve in the opposite direction. At the same time this construction permits 10 the quick and easy manual adjustment of the blades. Another important feature is that if either member 33 or 34 should be broken the remaining member would, through the gear connections shown, still 15 have perfect control of the blade to which the broken member was attached.

It is understood, of course, that while I have herein shown and described one embodiment of my invention, that changes in 20 form, proportions, construction and method of operation may be made within the scope of the appended claims.

I claim:

1. A propeller including a head fixedly 25 mounted on the propeller shaft, a pair of opposed bevel gears rotatably mounted in said head in parallel relation to said shaft,

a plurality of pinions revolvably mounted in said head in permanent mesh with said bevel gears, a propeller blade rigidly connected to each bevel gear in axial alinement therewith, and means for rotating said bevel gears and their respective blades a predetermined distance in opposite directions. 30

2. A propeller including a head fixedly 35 mounted on the propeller shaft and provided with bearings at right angles to said shaft, propeller blades provided with shafts to engage said bearings, each of said shafts having a bevel gear fixedly mounted on the end thereof and provided with spaced threaded portions between said gear and its respective bearing, a locking block provided with interior spaced threaded portions adapted to engage the spaced threaded portions of said shaft, means for locking said block to said gear when the threaded portions are engaged, a plurality of idler pinions mounted in permanent mesh with said gears, and means for rotating said propeller blade shafts a predetermined distance 40 in opposite directions. 45

P MARK WEDDELL.
